FIGURINE FOR DISPLAYING AN ADVERTISEMENT OR THE LIKE

Lloyd F. Golkowski, Garfield Heights, Ohio
Application July 28, 1959, Serial No. 56,962

Term of patent 14 years

(Cl. D1—2)

Fig. 1 is a front elevational view of a figurine for displaying an advertisement or the like showing my new design;

Fig. 2 is a right end elevational view thereof;

Fig. 3 is a left end elevational view thereof, the bottom of the figurine being substantially plain;

Fig. 4 is a top plan view thereof;

Fig. 5 is a rear elevational view on a reduced scale thereof; and

Fig. 6 is a fragmentary horizontal sectional view of the display area and tail and is taken on the line 6—6 of Fig. 1.

I claim:

The ornamental design for a figurine for displaying an advertisement or the like, as shown and described.
